CLAIM

The ornamental design for a water bottle accessory, as shown and described.

DESCRIPTION

FIG. 1 is a top isometric view of a water bottle accessory according to the present invention, in a first configuration. FIG. 2 is a bottom isometric view of the water bottle accessory of FIG. 1.

FIG. 3 is a top isometric view of the water bottle accessory of FIG. 1, in a second configuration.

FIG. 4 is a bottom isometric view of the water bottle accessory of FIG. 1, in a second configuration.

FIG. 5 is a front view of the water bottle accessory of FIG. 1.

FIG. 6 is a cross-sectional view of the water bottle accessory of FIG. 5, through lines 6-6.

FIG. 7 is a first side view of the water bottle accessory of FIG. 1.

FIG. 8 is a cross-sectional view of the water bottle accessory of FIG. 7, through lines 8-8.

FIG. 9 is a rear view of the water bottle accessory of FIG. 1. The side view opposite to that of FIG. 7 is identical.

FIG. 10 is a top view of the water bottle accessory of FIG. 1; and,

FIG. 11 is a bottom view of the water bottle accessory of FIG. 1.
